FONDUE WARMER

Victor J. Bergeron, Hillsborough, Calif., assignor to Senor Pico, Inc., San Francisco, Calif., a corporation of California

Filed May 25, 1967, Ser. No. 7,263

Term of patent 14 years

(Cl. D44—15)

FIG. 1.

FIG. 2.

FIG. 3.

FIG. 4.

The bottom of the lower member is plain and unornamented.

I claim:

The ornamental design for a fondue warmer, as shown and described.
